W. ABRAHAMS

MILITARY, POLICE, OR LIKE BELT

Filed Sept. 17, 1924

UNITED STATES PATENT OFFICE.

WILLIAM ABRAHAMS, OF PHILADELPHIA, PENNSYLVANIA.

MILITARY, POLICE, OR LIKE BELT.

Application filed September 17, 1924. Serial No. 738,127.

This invention, stated in its broadest terms, relates to an article of wearing apparel and has more especial relation to a military, police or like belt.

As at present manufactured, a belt of the character stated, is made in but one length so that a policeman, for example, is required to have one belt for use in winter and another belt for use in summer. The reason for this is that the type of belt under discussion is worn over an overcoat in winter time and requires an extra long belt, whereas, in summer time a shorter belt suffices. To manufacture said belts, which are usually of leather, requires the selection of a very good grade of material, free from flaws throughout its length which tends to materially increase the cost thereof. Another disadvantage of present belts is that in use the cartridge carrier tends to sag or fall away from the belt proper.

The leading object of the present invention is to overcome the above described disadvantageous features and provide a belt of the character stated which is readily adjustable for use both in winter and summer.

A further object is to provide a belt in which the waist strap is made in two parts so that extra long strips of leather are not required and in which short or scrap strips of leather may be utilized for the remainder thereof, thus tending to greatly reduce the cost of a belt of the type under discussion.

A further object is to provide a belt in which the cartridge carrier is detachably connected with respect to the relatively long and short waist straps in such manner as to preclude sagging of the cartridge carrier.

Other and further objects not at this time appearing will be referred to hereinafter.

The invention consists of the novel construction hereinafter described and finally claimed.

The nature, characteristic features and scope of the invention will be more fully understood from the following description taken in connection with the accompanying drawings forming part hereof, and in which:

Fig. 1, is a perspective view of a belt embodying features of the present invention.

Fig. 2, is a fragmentary view in elevation illustrating the parts extended to form a long belt.

Fig. 3, is a fragmentary view in plan illustrating the parts adjusted to form a short belt, and

Fig. 4, is a view in section taken upon the line 4—4 of Fig. 3.

For the purpose of illustrating my invention I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

Referring now to the drawings in detail, the numeral 1 designates a relatively long waist encircling strap and the numeral 2, a short section of strap. Usually such straps are of leather although obviously other material may be employed. Thus a very good grade of leather, free from flaws may be utilized for the long section of strap and short ends or scrap material may be used for making the sections 2. Thus, primarily, a belt of the type under consideration may be manufactured in a very economical manner. The numeral 3, designates a cartridge carrier which in the present invention is used as the medium for effecting joining together of the straps 1 and 2. One end of strap 1 is provided with an attachment, as a buckle 4, and strap 2 is apertured at 4', whereby the two ends of the belt may be secured together around the waist of the wearer. The opposite end of strap 1 is detachably secured in overlapping relation with respect to one end of cartridge carrier 3 by means, for example, of screws 5 which pass through registering apertures in the said strap and carrier and co-operatively engage washers 6 having screw-threaded openings therein. The cartridge carrier, adjacent its place of connection with strap 1, is apertured as at 7 for a purpose to presently appear. The opposite end of said cartridge carrier and the inner end of strap 2 are apertured so as to register in overlapping relation and are detachably connected by means, for example, of screws and washers similar in all respects to those previously described and which are designated 5' and 6' respectively. The cartridge carrier is provided with conventional cartridge receiving pockets 8 and is provided at each end with loops 8' through which in use, the belt parts 1 and 2 are passed.

With the parts arranged as above de-

scribed the belt is applicable for use over the overcoat of the wearer, the belt in this case being extra long. For summer use, with the overcoat discarded, obviously a shorter belt is necessary. Heretofore it has been necessary for the user to purchase a shorter belt. By the present invention, however, this disadvantage is overcome, it being merely necessary for the wearer to remove screws 5' and 6', cause the end of strap 2 to abut with the end of strap 1, replace said screws 5' and washers 6', and employ additional screws 5" and washers 6" to secure the strap 2 with respect to strap 1 and provide a relatively short belt. The strap 2 is provided with additional apertures 9 and the cartridge carrier is provided with additional apertures 7 in order that the parts may be adjusted as just described independently of the usual fastening buckle. Obviously an intermediate adjustment or adjustments may be effected by moving strap 2 toward or away from strap 1 any desired distance and employing screws and washers for effecting attachment of parts. For this purpose additional screws 11 and washers 12 may be temporarily fitted to apertures in the cartridge carrier and the strap 2 may be provided with additional apertures for registering with those of the cartridge carrier as is readily apparent. It is to be noted that the cartridge carrier, when attached with respect to straps 1 and 2, is firmly secured adjacent its top and bottom edges by the aforesaid screws and washers thus efficiently supporting the carrier to preclude sagging of the same under the weight of cartridges. Thus the cartridges may be maintained in a vertical position, which is desirable for ready withdrawal, and a better appearing article is provided which from the viewpoint of a military or police inspector is essential. The remaining parts of the belt are of conventional type and forming no part of the present invention require no description. While I have described a military or police belt of leather obviously belts of any material may be employed and further the adjustable feature of the invention is applicable to any form of belt. Obviously attaching mediums other than screws and washers may be used as snap fasteners or the like.

It will now be apparent that I have devised a novel and useful construction which embodies the features of advantage enumerated as desirable in the statement of the invention and the above description and while I have in the present instance shown and described the preferred embodiment thereof which has been found in prac-

tice to give satisfactory and reliable results, it is to be understood that the same is susceptible of modification in various particulars without departing from the spirit or scope of the invention or sacrificing any of its advantages.

What I claim is:

1. A military belt of the character stated comprising an elongated cartridge carrier, a relatively long belt portion detachably and adjustably secured to one end of said cartridge carrier, a relatively short belt portion having one end thereof detachably and adjustably secured to the other end of said cartridge carrier, and a buckle operatively interposed between the free ends of said two belt portions adjustably to secure the same to each other. 70 75

2. A military belt of the character stated comprising an elongated cartridge carrier having a series of cartridge sockets on the outer surface thereof, a belt guiding loop secured to the other side of said cartridge carrier at each of its opposed ends, a separate belt portion extending through each of said belt guiding loops and having its end overlapping the corresponding end of said cartridge carrier, means common to and extending through each of the ends of said cartridge carrier and the corresponding overlapping end of said separate belt portions detachably and adjustably to secure the ends of said belt portions to said cartridge carrier, and means adjustably to secure the free ends of said separate belt portions to each other. 80 85 90 95

3. A military belt of the character stated comprising an elongated cartridge carrier having a series of cartridge sockets secured to the outer surface thereof, a belt guiding loop secured to each end of said cartridge carrier on the other side thereof, a relatively long belt portion having an end extending through one of said belt guiding loops and overlapping the corresponding end of said cartridge carrier, a relatively short belt portion having an end thereof extending through the other of said belt guiding loops and overlapping the corresponding end of said cartridge carrier, a series of spaced apertures extending through the overlapping ends of said cartridge carrier, and the two belt portions, screws extending through said apertures for detachably and adjustably securing the ends of said two belt portions in overlapping relation to the corresponding ends of said cartridge carrier, and a buckle operatively interposed between the free ends of said two belt portions adjustably to secure the same to each other. 100 105 110 115 120

WILLIAM ABRAHAMS.
